UNITED STATES PATENT OFFICE.

JACOB F. LANGENAU, OF CLEVELAND, OHIO. ASSIGNOR TO THE LANGENAU MANUFACTURING COMPANY, OF CLEVELAND, OHIO, A CORPORATION OF OHIO.

FASTENING DEVICE.

Original application filed May 28, 1920, Serial No. 384,809. Divided and this application filed October 23, 1922. Serial No. 596,192.

To all whom it may concern:

Be it known that I, JACOB F. LANGENAU, a citizen of the United States, and a resident of Cleveland, county of Cuyahoga, and State of Ohio, have invented a new and useful Improvement in Fastening Devices, of which the following is a specification, the principle of the invention being herein explained, and the best mode in which I have 10 contemplated applying that principle, so as to distinguish it from other inventions.

The present improvements, relating, as indicated, to fastening devices, have more particular regard to locks or hasps of the sort 15 used on trunks, suit cases and the like, characterized by having a hasp in the form of a link that is carried by a pivotal member so as to engage with a hook-like member or projection when in locking position. The 20 object of the present invention is to provide supplemental means for securing such pivotal member in place when the hasp is in such locking position, the means ordinarily provided for this purpose consisting of a pin 25 or a stud member which more or less tightly fits into an aperture in the base plate to which said member is attached.

To the accomplishment of the foregoing and related ends, the invention, then, consists of the means hereinafter fully described and particularly pointed out in the claims, the annexed drawing and the following description illustrating but several of the various mechanical forms in which the principle 35 of the invention may be embodied.

In said annexed drawing:—

Fig. 1 is a front elevation or plan view of a fastening device embodying my present improvements, said device being shown in 40 its closed or locking position; Fig. 2 is a side elevation of said device with parts shown in section as indicated by the line 2—2, Fig. 1; Fig. 3 is a view similar to Fig. 1, but showing the pivotal hasp-carrying member removed so as to disclose more clearly the supplemental locking device; and Fig. 4 is a transverse section of such supplemental fastening device, the plane of the section being indicated by line 4—4, in Figs. 45 1 and 2.

Referring to the general assembly views as my improved device shown in Figs. 1 and 2, the familiar parts of the fastener comprise two base plates 1 and 2, which are

respectively designed to be secured in abutting relation to the main body and the cover or lid of a trunk, suitcase, or other similar article. Rigidly attached to said plate 1 is a hook-like projection 3, the undercut face of which extends in a direction away from the edge of the plate that lies in abutting relation to plate 2. Rigidly attached to the latter in turn is a projection 4, preferably in the form of a hollow boss, to the outer edge of which is pivotally attached 55 by means of a pin 5, a hollow member 6 having swingably secured thereto a link 7, which constitutes the aforesaid hasp. The free end of this link, in other words, is adapted, when member 6 is swung outwardly, to engage beneath the hook-like projection 3 on plate 1, and when said member is thereupon pressed backwardly against the plate 2, the two plates, with the parts of the trunk or equivalent article will be forcibly 60 drawn together.

As shown in Fig. 2, the pivotal axis 5 of the member 6 should lie without the plane of the link in the locking position of the parts just described so as to minimize any tendency on the part of member 6 to swing outwardly to releasing position; however, I have found it desirable to add a supplemental locking device in order to secure 70 against any but purposeful opening of the 75 lock.

With this in view, the upper end 8 of the member 6, which is curved to present a convenient finger piece for operation of the lock, as best illustrated in Fig. 2, is provided with a necked stud 20 fixedly secured thereto, such stud, in a locking position of the parts, being arranged to project through an aperture 21 in plate 2. The portion of 80 said plate, in which aperture 21 is thus formed, is preferably raised to provide a flat boss, and in the recess thus provided on the rear or under-face of the plate, a re-curved spring 22 is housed, the arms of such spring normally intersecting the aperture 85 and being adapted to grip the sides of the stud 20 in the fashion best shown in Fig. 4. The action, in other words, is somewhat 90 similar to that of a snap fastener in that the head of the stud 20 is rounded so that upon 95 being forced into opening 21, it will spread the two arms of spring 22 apart and the latter then will engage with the reduced 100 105

portion or neck of said stud and thus hold the latter against accidental dislodgment from such aperture 21. Spring 22 is conveniently held in place by means of a cover plate 23 that closes the depression formed by the boss in which such aperture 21 is formed, such plate and the spring being secured to the under-face of the part 2 by means of a rivet 24, as clearly shown in 10 Figs. 2 and 3.

The foregoing supplemental locking device, it will accordingly be seen, affords a simple and yet effective agency for retaining the member 6 with the hasp 7 in locking position. There is, of course, no particular strain placed upon the stud 20, so that the parts of such supplemental locking device may be made of relatively light construction, and yet prove sufficiently substantial for the purpose in hand.

Inasmuch as the hereinbefore described construction of locking device was originally disclosed as a modification of the device which forms the subject matter of my 25 co-pending application, filed May 28, 1920, Serial No. 384,809, the present application is to be regarded as a division or continuation of such co-pending case.

Other modes of applying the principle of 30 my invention may be employed instead of the one explained, change being made as regards the mechanism herein disclosed, provided the means stated by any of the following claims or the equivalent of such stated 35 means be employed.

I therefore particularly point out and distinctly claim as my invention:—

1. In a fastening device of the character described, the combination with two plates 40 designed to be secured in abutting relation on the parts to be fastened together, a hook-like projection rigidly mounted on one of said plates, a member pivotally attached to the other plate, and a link carried by said 45 member and adapted to engage said projec-

tion to lock said plates together, said member being provided with a necked stud adjacent its free end; of a resilient member secured on the corresponding plate adapted to engage such stud and thus to retain said 50 member against accidental movement.

2. In a fastening device of the character described, the combination with two plates designed to be secured in abutting relation on the parts to be fastened together, a hook-like projection rigidly mounted on one of said plates, a member pivotally attached to the other plate, and a link carried by said member and adapted to engage said projection to lock said plates together, said member being provided with a necked stud adjacent its free end and the corresponding plate being formed with an aperture disposed to receive such stud; of a spring secured to the rear face of said plate and adapted to engage with such stud when thus received in such aperture and thereby retain said member against accidental movement.

3. In a fastening device of the character described, the combination with two plates 70 designed to be secured in abutting relation on the parts to be fastened together, a hook-like projection rigidly mounted on one of said plates, a member pivotally attached to the other plate, and a link carried by said member and adapted to engage said projection to lock said plates together, said member being provided with a necked stud adjacent its free end and the corresponding plate being formed with a raised boss having 75 an aperture disposed to receive such stud; of a recurved spring secured to the rear face of said plate in a recess formed by such boss, the arms of such spring normally intersecting such aperture and being adapted to grip 80 the sides of such stud when thus received in such aperture and thereby retain said member against accidental movement.

Signed by me this 19 day of Oct., 1922.

JACOB F. LANGENAU.
